UNITED STATES PATENT OFFICE.

WILLIAM C. HOLLAND, OF TUSCUMBIA, ALABAMA.

DRAFT APPLIANCE FOR LOCOMOTIVE SMOKE BOXES.

Application filed May 18, 1923. Serial No. 639,951.

To all whom it may concern:

Be it known that I, WILLIAM C. HOLLAND, a citizen of the United States of America, residing at Tuscumbia, in the county of 5 Colbert and State of Alabama, have invented certain new and useful Improvements in Draft Appliances for Locomotive Smoke Boxes, of which the following is a specification.

10 My invention relates to improved draft appliances for use in railway smoke boxes, and its object is to so control, regulate and direct the draft through the smoke box that there is a better distribution of the 15 draft throughout the boiler tubes and fire box, and that there is a more accurate and effective control of the draft in the smoke box to the end that the exhaust nozzle tip may be opened to the maximum desired extent, without unduly intensifying the draft, thereby to reduce back pressure in the cylinders to a minimum, and to obtain a more efficient steaming action from the locomotive and a lower fuel consumption.

20 One distinctive feature of my invention consists in the provision in the bottom of the smoke box of an upwardly and forwardly inclined baffle which at its upper edge leaves a relatively small clearance between it and the forward edge of the table plate, thus providing a relatively narrow 25 draft opening extending transversely the width of the smoke box nearly in line with the lower large flues. The purpose of this 30 is to raise the direct line of the draft and hence increase the direct flow of the gases through the center tubes of the boiler, where there is greatest need for same, due both to the presence of the superheater tubes there 35 and to the use of larger flues at the center.

40 My invention also contemplates the provision of an adjustable baffle underhung from the forward edge of the table plate to afford the requisite draft regulation at 45 this point.

Another feature of my invention consists 50 in elongating the barrel of the petticoat to bring it close to the top of the smoke box saddle thereby to reduce the overdraft to the extent desired.

55 A further distinctive feature of my invention consists in the deepening and lateral elongation of the flare of the petticoat so as to provide it with a relatively narrow intake opening extending substantially the full distance between the steam pipes at the

sides of the smoke box, said opening being disposed at a level much closer to the table plate than is at present the general practice. This arrangement results in a more effective distribution laterally of the draft and avoids the quick concentration of the products of combustion at the center to enter the flare of the ordinary petticoat. To compensate for the reduced overhead draft 60 opening I increase the diameter of the petticoat barrel, thus giving it the capacity to collect through its flare transversely of the smoke box and substantially uniformly, the gases flowing in a narrowed transverse 65 stream between the table plate and lower baffle.

70 My invention also contemplates the provision at the lower forward edge of the petticoat flare of an adjusting draft plate which 75 will care for such regulation as is needed for the draft at this point.

80 My invention also comprises the novel details of construction and arrangement of parts, which in their preferred embodiment only are illustrated in the accompanying drawings which form a part of this specification, and in which:—

85 Fig. 1 is a vertical longitudinal cross-section through a typical locomotive smoke box 85 equipped with my improved draft appliances.

90 Fig. 2 is a transverse cross-sectional view taken through the smoke box on the line 2—2 of Fig. 1.

95 Similar reference numerals refer to similar parts throughout the drawings.

100 In the embodiment of my invention illustrated, I show a locomotive boiler 1 having the usual forward tube sheet 2 in which are mounted smaller tubes 3 which surround the larger central tubes 4. The superheater units 5 are conventionally shown, one being illustrated entering a larger tube 4. A vertical baffle 6 is interposed in front of the 105 superheater appliances extending from the superheater header downwardly to the table plate 8, which extends forwardly and horizontally therefrom and terminates in a short downwardly inclined flange 9. An inclined 110 baffle sheet 10 leads upwardly and forwardly from the bottom of the smoke box near the flue sheet 2 to a point below and slightly in front of the flange 9, there being an elongated draft opening thus provided between the baffle and table plate which stands nearly in line with the lower of the large

2

tubes 4. The steam exhaust stand 11 passes up through the table plate in the customary manner and discharges the exhaust steam into the petticoat flare 12 which merges into the cylindrical petticoat barrel 13 provided with the usual hangers 14 to which the hanger straps 15 are attached. It will be observed that the upper end of the barrel 13 rises to a point close to the smoke stack saddle 16. In practice I have successfully used a clearance of about 2½ inches between the top of the barrel and the top center of an 80 inch smoke box. The petticoat flare is deeper than that customarily used, extending in such a smoke box 14 inches below the base of the petticoat barrel as compared with ordinary depth of about 5½ inches. This drops the bottom end of the petticoat flare much closer than usual to the table plate and the exhaust tip 11^a, its height in said smoke box above the table plate being 12 inches. The flare is laterally elongated to extend substantially from side to side of the smoke box between the steam pipes 17 (see Fig. 2). In width the flare is relatively narrow at its bottom or intake end, and in width corresponds approximately to the width of the table plate. The forward edge of the petticoat flare has adjustably attached thereto a draft regulating plate 18 adapted to control the draft at this point, and the table plate flange 9 has adjustably attached thereto a draft regulating plate 19 to control the draft through opening 20, netting 21 and the superheater damper 22.

In the practice of my invention, the outlet of the exhaust tip 11^a is enlarged sufficiently to avoid the creation of any objectionable back pressure in the cylinders. The long narrow draft opening 20, formed between the baffle 10 and table plate flange 9, effects a very desirable transverse distribution of the draft and the elongated petticoat takes this widely distributed draft and collects and carries it up to the smoke stack in the most desirable manner, leaving no accumulation of cinders or foreign matter in the smoke box. The smoke box is equipped with the usual standard netting 21.

Having mounted the draft appliances in the manner described, and adjusted the two draft plates 18 and 19 to meet the operating conditions in the case at hand, the operation of my invention results in a lifting of the level of the draft nearer into line with the

large center flues, thus bringing the products of combustion in greatest volume more directly through the center of the boiler and producing a much more efficient steaming action than is at present obtainable and a much better draft action on the fire bed.

Having thus described my invention, what I claim as new and desire to secure by Letters Patent, is:—

1. A locomotive smoke box having a table plate and an upwardly and forwardly inclined baffling draft sheet leading from the bottom of the smoke box and extending transversely thereof and terminating in spaced relationship with the front end of the table plate to form therewith a raised, relatively narrow laterally elongated draft opening.

2. A locomotive smoke box according to claim 1, having a tube sheet with its largest tube openings disposed in its central position, said draft opening being raised into line with the lower of said largest tube openings.

3. A locomotive smoke box according to claim 1, in which a draft regulating damper plate is adjustably mounted for movement across said draft opening.

4. A locomotive smoke box having a table plate, a lower baffle associated with said plate to form a narrow wide draft opening, and a petticoat having its flare narrowed and laterally elongated to correspond substantially with the width of the table plate.

5. A locomotive smoke box having a table plate, and a petticoat having its flare narrowed and elongated to correspond substantially with the transverse width of the table plate and disposed to extend substantially from side to side of the smoke box.

6. A locomotive smoke box according to claim 5, in which the petticoat barrel is enlarged and extended upwardly into close juxtaposition to the top of the smoke box.

7. A locomotive smoke box according to claim 5, in which the bottom inlet end of the flare is lowered into relatively close juxtaposition to the table plate.

8. A locomotive smoke box according to claim 5, in which the draft opening between the forward edge of the flare and the table plate is controlled by an adjustable damper.

In testimony whereof I affix my signature.

WILLIAM C. HOLLAND.
